UNITED STATES PATENT OFFICE.

GEORGE BRASSFIELD TAYLOR, OF BELFAST, IRELAND.

BOX, FOLDER, AND LIKE CONTAINER.

1,425,720.

Specification of Letters Patent. Patented Aug. 15, 1922.

Application filed June 20, 1921. Serial No. 478,967.

To all whom it may concern:

Be it known that I, GEORGE BRASSFIELD TAYLOR, of 9 Brunswick Street, Belfast, Ireland, have invented certain new and useful Improvements Relating to Boxes, Folders, and like Containers, of which the following is a specification.

This invention relates to boxes, folders and like containers such for example as are 10 used for containing handkerchiefs, gloves and various other articles or goods and of the class in which the container is decorated for display purposes or for the purpose of making it more attractive. At present 15 boxes, folders and containers of this class are usually thrown away when the articles have been taken out of same.

Under my invention I provide a calendar or the like and attach it to one end of the lid 20 or top of the box, folder or like container by ribbon or other flexible connecting means, so that the calendar or the like can be folded under the lid or top of the box or under the top of the folder when the lid is on the 25 box, or the top is folded down, to enclose the goods. At the opposite end of the box lid, or folder top, I provide a ribbon or equivalent means for hanging up the same on a nail or the like. The arrangement is 30 such that the box lid or folder top, as the case may be, in addition to serving its ordinary purpose also provides a decorative calendar or the like for hanging up on a wall and is adapted for advertising purposes. 35 In the case of a folder top it may be so connected with the other portion of the folder as to be readily detachable therefrom when desired.

The invention will now be described with 40 reference to the accompanying drawings whereon:

Fig. 1 is an isometric view of a box lid or top with the calendar and the hanging ribbon folded in.

45 Fig. 2 shows the box lid or top hung up and in use as a calendar.

Fig. 3 is an isometric view showing the invention applied to a folder as used for containing articles and goods, such as handkerchiefs, and the like, the calendar and the hanging ribbon being shown folded in.

50 Fig. 4 is an isometric view showing the folder in use as a calendar.

Fig. 5 is a perspective view of a box or

container constructed according to this invention.

In the example shown at Figs. 1 and 2, the box lid 1 is provided with flanges 1^a at right angles to the body of the lid and is provided with a hanging ribbon 2 secured at one end and a calendar 3 is secured by ribbons 4 to the opposite end in such manner that when the lid 1 is hung, or suspended, such as on a nail as shown at Fig. 2, the calendar 3 will be suspended below 65 the lid 1. The outer surface of the lid is, preferably, provided with a picture and (or) advertising matter printed or otherwise displayed thereon.

A box or container provided with a lid or 70 top according to Figs. 1 and 2, is shown in Fig. 5, in which the flanges 1^a are seen fitted on to the sides 1^b of the body of the box or container.

In the example shown at Fig. 3, the invention is applied to a folder 5 to the top margin of which the ribbon 6 is secured, whilst the calendar 7 is secured by ribbons 8 to the bottom margin of the top of the folder. The folder is shown in use as a 80 calendar at Fig. 4. The outer surface of the top of the folder may have a picture and (or) advertising matter printed thereon, as desired.

Other portions of the box lid or folder 85 may be suitably decorated or otherwise treated as desired.

Having now fully described my invention, what I claim and desire to secure by Letters Patent is:—

1. A new article of manufacture comprising, in combination, a top for a container adapted to hold handkerchiefs, gloves and like articles, a calendar flexibly attached to one end thereof, and a flexible means at 95 the other end for suspending the top and calendar.

2. A new article of manufacture comprising, in combination, a top for a container adapted to hold handkerchiefs, gloves and like articles and formed with flanges, a calendar flexibly attached to one end thereof, and a flexible hanging ribbon.

3. A new article of manufacture comprising, in combination, a container, a top for 105 the container, a calendar flexibly connected to one end of the top, and a hanging ribbon connected to the other end of the top.

4. A new article of manufacture comprising, in combination, a container, a top for the container, a calendar secured by ribbons to the inside of one end of the top, and 5 a hanging ribbon secured to the inside of the other end of the top.

5. A new article of manufacture, comprising, in combination, a box body with 10 sides, a lid with flanges which fit the sides of the body, a calendar connected by rib-

bons to the flange at one end of the lid, and a hanging ribbon secured to the flange at the other end of the lid.

In testimony whereof I affix my signature in presence of two witnesses.

GEORGE BRASSFIELD TAYLOR.
